UNITED STATES PATENT OFFICE.

DAVID B. LINCOLN, OF AURORA, ILLINOIS, ASSIGNOR TO JOHN A. MANLY, OF GRAND RAPIDS, MICHIGAN, AND CHARLES T. DAILY, OF KANSAS CITY, MISSOURI.

ADVERTISING-CABINET.

SPECIFICATION forming part of Letters Patent No. 486,113, dated November 15, 1892.

Application filed December 28, 1891. Serial No. 416,290. (No model.)

To all whom it may concern:

Be it known that I, DAVID B. LINCOLN, of Aurora, in the county of Kane and State of Illinois, have invented certain new and useful 5 Improvements in Advertising-Cabinets for Hotel-Counters, of which the following is a specification.

This invention relates to an advertising-cabinet for hotel-counters, the cabinet being 10 adapted for the display of advertisements and also for the reception of a bell, ink-wells, envelopes, telegrams, and the like.

The invention relates particularly to a construction of the cabinet which will permit the 15 changing of the advertisements at will. To this end the cabinet is constructed, preferably, from metal, and is provided on its upper surface, and, also, if desired, upon its front edge with ways within which small metal 20 plates, hereinafter called "cards," may be arranged and removably clamped to secure them in place and yet permit them to be shifted or changed, as desired. The cards are made from metal for the reason that they are not im- 25 paired by continued use and can be kept bright and clean, so that the advertisement will be continually fresh and attractive in appearance. The matter of advertisement may be engraved on the faces of the cards or sten- 30 cilled or stamped thereon, and the cards will preferably be made in some definite proportion or size with reference to each other and removably secured upon the cabinet so that they may be readily shifted or changed, as 35 occasion may require.

In the accompanying drawings, Figure 1 is a side elevation of the cabinet, showing cards upon its front and the usual accessories and also a statuette thereon. Fig. 2 is a plan view 40 of the same with the statuette and bell omitted, and Fig. 3 is a vertical section on the line 3 of Fig. 2.

The body A of the case may be cast in one piece of metal or made in sections properly 45 secured together, if preferred. In form the case may be round, square, or oblong, the latter being the form shown in the drawings. I prefer to cast the body hollow and to brace it by means of the stays or brace-rods B. Any 50 desired number of depressed receptacles C D E F G may be provided in the surface,

which may be used, respectively, for envelopes, cards, matches, ink-wells, shot, &c.

A bell H is mounted on the top plate of the cabinet and a statuette may occupy a central 55 position thereon, as shown. On the upper surface are secured the strips or plates I, having their lower inner edges grooved or cut away, as at i, to form ways within which may be slipped the metal cards J. These cards, as 60 shown, are of rectangular shape and all of the same size, but they may vary as to size. Their ends are confined by the strips I, and upon them is placed the matter of advertisement, preferably by engraving. The rear ends of the 65 strips I are joined by the transverse strip K, and the removable stop-piece L is screwed to the body A, so as to hold all the cards in place and prevent their being slipped out or shifted by accident or by thoughtless or meddlesome 70 persons. The front of the cabinet is also utilized for the reception of cards, as shown in Fig. 1, and these cards may be readily shifted, whenever desired, by removal of the stop-piece L, and the cards may be slipped out and 75 shifted as to position or replaced by new cards. This feature of the invention is particularly desirable, because by reason of changes in business and for other causes 80 changes in the advertisements are often desired. Therefore if all the cards were engraved or otherwise placed upon a single strip of metal, it would entail the expense of an entire new plate containing the business cards of the various advertisers in order to make a 85 change in a single advertisement. I therefore make the cards independent of each other and all readily removable or detachable from the cabinet, so that they can be rearranged or replaced at will. I do not, of course, limit my 90 invention to precise details of construction.

I claim—

1. An advertising-cabinet for hotel-counters, comprising, in combination, a hollow metal body having braces upon its interior, 95 sunken or depressed receptacles formed integral with the body, grooved metal strips upon its surface and front, providing ways, and a series of independent metal advertising-cards adapted to be clamped within the ways, sub- 100 stantially as described.

2. A cabinet for hotel-counters, comprising,

in combination, a hollow metal body having suitable braces on its interior, and sunken or depressed receptacles therein, and having grooved metal strips upon its surface, providing slideways open at one end, a series of independent metal advertising-cards adapted to be placed in the slideway, and a strip re-

movably secured in the open end of the slide-way to confine the cards therein, substantially as described.

DAVID B. LINCOLN.
